UNITED STATES PATENT OFFICE.

DANIEL B. LITTLEFIELD, OF CHICAGO, ILLINOIS.

SUSTAINING AND PROPELLING MECHANISM.

No. 882,899.

Specification of Letters Patent. Patented March 24, 1908.

Application filed February 27, 1907. Serial No. 359,688.

To all whom it may concern:

Be it known that I, DANIEL B. LITTLEFIELD, a citizen of the United States, and a resident of the city of Chicago, in the county 5 of Cook and State of Illinois, have invented certain new and useful Improvements in Sustaining and Propelling Mechanism; and I do hereby declare that the following is a full, clear, and exact description of the same, reference being had to the accompanying drawings, and to the letters of reference marked thereon, which form a part of this specification.

This invention relates to improvements in 15 sustaining and propelling mechanism and has for its object more particularly a mechanism adapted to elevate sustain and propel airships or other fluid sustained devices.

It is an object of the invention to provide a 20 construction in which the propelling mechanism acts also to sustain the weight and in which the propellers act both vertically and obliquely.

It is also an object of the invention to 25 afford reciprocating propellers whereby the normal effect of the propellers is augmented.

It is also an object of the invention to provide a construction affording a plurality of propellers some of which act vertically 30 while the others act obliquely and to afford a construction in which a plurality of propellers are used all of which rotate, reciprocate and oscillate rhythmically.

It is a further object of the invention to 35 provide in combination with suitable sustaining and propelling mechanism aeroplanes which act to steady and sustain the flight.

It is finally an object of the invention to 40 afford an exceedingly light, strong and compact mechanism of the class described by the use of which sustained and dirigible flight is possible.

The invention consists in the matter hereinafter described and more fully pointed out and defined in the appended claims.

In the drawings: Figure 1 is a side elevation partly broken of a device embodying my invention. Fig. 2 is a top plan view of the 50 same. Fig. 3 is a fragmentary detail of the adjusting mechanism for varying the angle of operation of the propellers. Fig. 4 is an enlarged inner face view of the planetary gear and pinion embodied in my invention. Fig. 5 is a section thereof taken on line 5—5 55 of Fig. 4. Fig. 6 is an enlarged sectional

detail taken on line 6—6 of Fig. 4. Fig. 7 is a fragmentary detail illustrating the support for the rudder and the tiller lines therefor.

As shown in the drawings:—Referring 60 first to Fig. 1, a rectangular frame is provided comprising strong but light steel or other suitable tubes A, disposed at the corners thereof and are connected at the top by means of suitable fittings with horizontal 65 tubes a, and near their lower ends with tubes a'. Any suitable fittings may be employed for this purpose, the object being to attain maximum rigidity and strength with minimum weight and of course braces may 70 be provided where required. Said tubular posts A afford legs upon which the machine may rest when on the ground. The upper frame members a at each side of the frame are extended beyond the vertical posts A, 75 affording extensions a³ at the outer end of which are suitable boxes which afford bearings for lateral horizontal shafts B each provided with a collar b at each end thereof which bears against the inner side of said 80 extension or arm a³. Said shafts at each end extend beyond the arm a³ and rigidly keyed thereon is the radially extended arm c of a beveled gear C. Journaled at the middle of said bevel gear C is a shaft c' which, as 85 shown, at its end closely adjacent the face of said gear, is provided with a sleeve c² in which is journaled the propeller shaft D.

On the upper end of each propeller shaft 90 is a propeller wheel having any desired number of propeller blades and indicated as a whole by D', D², D³ and D⁴, on the respective shafts, which are four in number, one being at each corner of the machine. Rigidly secured on each shaft D to mesh with the 95 bevel gear C, is a beveled pinion d and likewise rigidly secured on the shaft D above and below the bearing sleeve c², are collars d' and d² which act at all times to hold said pinion in mesh with said gear. The lower 100 ends of said shafts D, extend through suitable sleeves e provided at opposite ends of longitudinally adjustable adjusting rods E, also tubular for lightness and which are slidable in brackets e' rigidly secured on the 105 lower longitudinal frame members a'. Said adjusting rods E, are provided each with a rack e² at its middle part adapted to be engaged by a pinion e³, rigidly engaged on a suitable shaft e⁴, journaled transversely the 110 machine on said lower frame members and as shown a hand wheel e⁵ is provided on said

shaft whereby the same may be rotated to shift said adjusting bars forwardly or rearwardly thus varying the angle of operation of pull of the propellers on the shafts D, as shown in Fig. 1. The operator's platform is conveniently supported on said lower frame members a' and may be constructed in any suitable manner to enable the operator to sit, stand or lie conveniently to the mechanism of the machine. Positioned centrally on said platform as shown is an explosive engine or other suitable motor F, which drives a sprocket wheel f, secured on its crank shaft, about which and suitable sprocket wheels, b², secured on the shafts B is trained a sprocket chain f' whereby said engine or motor drives all said shafts and propellers continuously.

At the rear of the machine and hinged to a post g is the rudder G, which may be of any suitable size or shape and may be operated in any suitable manner. As shown, however, tiller lines g', g² lead from the outer end of the rudder inwardly to the operating station in convenient access to the operator and can be operated either by a suitable wheel or in any suitable or convenient manner.

The operation is as follows:—The frame which is exceedingly light and rigid as before described is supported in an upright position upon any suitable surface or may be mounted on wheels if desired and the motor is started. The action of the motor drives the propellers each in the appropriate direction to afford the maximum lifting effect and as said shafts B rotate, the gears C swing about the same in a circle, so that each rotation of the shafts B acts to raise the shaft D actuated thereby vertically, swing the upper or propelling end of the same forwardly and as the gear C descends, retracts the shaft pulling the propeller downwardly and obliquely toward the rear. Said gears C are so arranged upon their respective shafts that the diagonally opposite propellers act together in pairs, that is to say, the propellers D' and D³ are rising, while the propellers D² and D⁴ having swung forward are descending as shown in Fig. 1. In this manner two of said propellers are at all times acting at their maximum power both to support and to draw the device ahead, while the remaining two are rising but are nevertheless supporting the device with near their maximum effect inasmuch as the pitch and lead of the propellers and the rate of rotation thereof are such as to avoid back pressure due to the raising of the propellers. The angle of operation of the propellers can of course be varied by means of the hand wheel e⁵, which simultaneously shifts the adjusting rods E rearwardly or forwardly. When adjusted for slight angles of inclination upon the shafts the effect produced will be mainly a lifting effect and if shifted rearwardly as shown in

Fig. 1, a decided pulling effect is produced by said propellers during half of the rotation or gyration of the gear C, the remaining half of the period of rotation said propellers are mainly acting as supports.

From the construction described it is obvious that the forward motion of the device is caused by the forward pull of the propellers which tend to cause the center of gravity to swing forwardly successively as the shafts 75 or propellers gyrate. The rudder acts to steady the forward movement and prevent oscillation in the car as well, as to guide the same and for the purpose of further steady- 80 ing the car but principally to aid the same in sustaining continuous flight, aeroplanes H consisting of substantially parallel planes of considerable length are provided transversely and centrally of the machine. These are secured at their front edges on a vertical 85 bar or rod h, secured on the bottom and top of the frame on the frame members a and a', respectively. At the rear side said aeroplanes are connected by means of a rod h', which may be hinged thereto and which 90 afford means for varying the angle at which said aeroplanes impinge on the air while the car is in flight. Any suitable mechanism may be employed for adjusting the aeroplanes.

Obviously while I have described my invention as embracing upper propellers only, other propellers may be provided which may serve the purpose only of propelling while the remaining propellers lift the device. 100 These may or may not oscillate or gyrate as desired, and if desired of course many variations in details may be effected without departing from the principles of this invention. I therefore do not purpose limiting this application for patent otherwise than as necessitated by the prior art.

I claim as my invention:—

1. A propeller adapted to rotate, reciprocate and oscillate simultaneously, and a motor for actuating the propellers.
2. A propeller adapted to rotate, reciprocate and oscillate simultaneously, and means varying the angle of oscillation and reciprocation.
3. A propeller and mechanism acting to rotate, gyrate and reciprocate the propeller.
4. In a device of the class described a propeller and mechanism acting to continuously rotate and to reciprocate and gyrate the same, the gyrations and reciprocations being synchronous.
5. The combination with a suitable motor, of propellers driven thereby, means simultaneously reciprocating and oscillating said propeller during rotation thereof and means varying the angle at which the same reciprocates.
6. In a device of the class described the combination with a suitable motor, of a rigid

shaft driven thereby, a planetary gear operated thereby and a propeller rotated, reciprocated and gyrated thereby.

7. In a device of the class described the 5 combination with a suitable frame, of a rigid shaft driven thereby, a planetary gear operated thereby, a propeller rotated, reciprocated and gyrated thereby, and means for varying the direction of gyration and reciprocation.

8. In a device of the class described the combination with a suitable frame, of rotary and reciprocating propellers thereon arranged in pairs, means actuating the same 15 whereby one pair rises while the other descends, and means varying the angle of operation of the propellers.

9. The combination with a suitable frame, of propellers arranged one at each corner 20 thereof, a planetary gear acting to rotate and to reciprocate and oscillate said propellers in diagonally opposite pairs, one set acting to rise as the other descends, mechanism for varying the angle of operation of the propellers and aeroplanes secured on said frame.

10. In a device of the class described the combination with a suitable frame, of a motor thereon, a shaft journaled on the frame, a beveled gear rigidly engaged on 30 said shaft, eccentric thereto, a shaft extending through the center of said gear, a sleeve thereon adjacent the face of the gear, a propeller shaft journaled in said sleeve, a beveled pinion rigidly secured on said shaft, a 35 propeller on the shaft and adjustable means engaged on said frame and acting to shift the end of said shaft laterally to vary the angle of operation of the propeller.

11. In a machine of the class described a 40 frame, a propeller above each quarter thereof, means rotating the propellers and mechanisms reciprocating and gyrating the same in diagonally opposite pairs.

12. In a machine of the class described a 45 frame, a propeller above each quarter thereof, a motor rotating the propellers and mechanism driving each propeller to gyrate and rotate the same in pairs, one pair moving downwardly and obliquely rearwardly while 50 the other moves upwardly and means varying the angle of such movement.

13. In a machine of the class described a 55 frame, a propeller above each quarter thereof, a motor rotating the propellers and mechanism driving each propeller to gyrate and rotate the same in pairs, one pair moving downwardly and obliquely rearwardly while the other moves upwardly and means varying the angle of such movement, and aeroplanes arranged on said frame.

14. In a machine of the class described a 60 frame, a propeller above each quarter thereof, a motor rotating the propellers, mechanism driving each propeller to gyrate and rotate the same in pairs, one pair moving down-

wardly and obliquely rearwardly while the other moves upwardly and means varying the angle of such movement, aeroplanes arranged on said frame, and a rudder to direct the flight.

15. In a device of the class described the combination with a frame, a motor and horizontal shafts on said frame driven thereby, of beveled gears, an arm engaged on each extending beyond the periphery thereof and 70 rigidly engaged on the ends of said shafts whereby said gear as a whole swings about the shaft during each rotation, a propeller shaft journaled at the center of each gear and parallel with the face thereof, beveled 75 pinions thereon meshing with said beveled gear, a propeller on the outer end of each propeller shaft, adjusting mechanism at the inner end of each propeller shaft adapted to swing the same longitudinally of the frame. 80

16. In a device of the class described the combination with a frame, a motor and horizontal shafts on said frame driven thereby, of beveled gears, an arm engaged on each extending beyond the periphery thereof and 90 rigidly engaged on the ends of said shafts whereby said gear as a whole swings about the shaft during each rotation, a propeller shaft journaled at the center of each gear and parallel with the face thereof, beveled 95 pinions thereon meshing with said beveled gear, a propeller on the outer end of each propeller shaft, adjusting mechanism at the inner end of each propeller shaft adapted to swing the same longitudinally of the frame, 100 said beveled gears being so arranged on their shafts that some of said propellers are rising while the remaining are moving rearwardly and downwardly.

17. In a flying machine rotating propellers 105 gyrating and reciprocating synchronously the gyrations and reciprocations acting to pull the same ahead, and aeroplanes to support the device during flight.

18. The combination in a flying machine 110 of four propellers one above each quarter and acting by rotation to lift the car, means rotating the same, part of which move downwardly and obliquely and part of which simultaneously move upward and obliquely 115 and means varying the angle of action of said propellers to pull the same forwardly, and aeroplanes secured on said machine.

19. The combination with a body to be driven, of a propeller secured thereto and 120 means simultaneously oscillating, rotating, reciprocating and gyrating the same rhythmically.

20. A sustaining and propulsion propeller, means gyrating, reciprocating and oscillating 125 the same synchronously and rhythmically and means for varying the angle of operation.

21. In a device of the class described the combination with a frame of parallel driven 130

shafts journaled thereon, propeller shafts, means rigidly and eccentrically secured on each end of the driven shafts and pivotally engaging one of the propeller shafts adapted to rotate and oscillate the shaft and a propeller on each shaft.

22. In a device of the class described the combination with a frame of driven shafts secured thereto, propeller shafts, a universal connection at one end of each propeller shaft, a pivotal connection at the opposite ends of the propeller shafts, a propeller on each propeller shaft, means operated by the driven shafts to impart a sustaining stroke to part 15 of said propellers and means simultaneously imparting a propulsion stroke to other of said propellers.

23. In a device of the class described the combination with a frame and motor secured thereto, a shaft driven by said motor, a gear secured thereto, a propeller shaft having a pivotal connection at one end with said gear and a universal connection at its opposite end with the frame, said gear alternately 20 25 imparting a sustaining and a propelling impulse to said propeller shaft and a propeller operated by the propeller shaft.

24. In a device of the class described the combination with a frame, of propellers secured thereto, and eccentric means imparting a sustaining impulse to part of said propellers and simultaneously imparting a propulsion impulse to other of said propellers.

25. In a device of the class described the

combination with a frame of propellers secured thereto and means simultaneously reciprocating and rotating each propeller imparting propulsion strokes to part thereof and sustaining strokes to the remainder of the propellers.

26. In a dirigible air navigating device the combination with a frame of a motor secured thereto, a shaft driven by said motor, propellers operatively connected with said shaft, means imparting sustaining and propulsion strokes rhythmically to said propellers and means for guiding the movement of the device.

27. In a device of the class described the combination with a suitable frame and support of a motor secured thereon, shafts driven by said motor, propellers journaled on the frame, means operated by said shafts for rotating, reciprocating and oscillating the propellers, means operated from the platform for varying the angle of operation of the propellers, a rudder operated from the platform to guide the direction of the device, aeroplanes comprising blades engaged to the frame and means adjusting the angle of inclination of the blades.

In testimony whereof I have hereunto subscribed my name in the presence of two subscribing witnesses.
